FOUNTAIN PEN

Robert Peter Markstein, Vienna, Austria

Original application July 9, 1929, Serial No. 376,972, and in Austria March 23, 1929. Divided and this application January 7, 1932. Serial No. 585,344

3 Claims. (Cl. 120—49)

My invention relates to fountain pens consisting of a tubular system which comprises a nib carrier and a nib protecting shell slidably mounted in said tubular system.

5 This application is a division of my copending application for Letters Patent of the United States for improvements in fountain pens, filed July 9, 1929, Serial No. 376,972.

The invention has for its object to provide 10 means for sufficiently securing the protecting shell in its outmost position in relation to the nib carrier, so that said protecting shell is prevented in its outmost position from casually moving inwards. Moreover the invention comprises means for limiting the stroke of this protecting shell.

According to the invention a spring member 20 is provided which engages said shell in its outmost position and thus secures the same sufficiently. The tubular system includes an outer tube, an inner tube connected thereto and forming the nib carrier and a protecting shell, a spring pawl being provided which may be formed by a longitudinal cut out portion of the wall of the inner tube and engages the said protecting shell in its outmost position.

The spring member may also be formed by a portion cut out from the wall of the inner tube.

One portion of the tubular system may have 30 a projection and another portion thereof a longitudinal groove said projection engaging said groove for limiting the stroke of the protecting shell.

In the drawing Fig. 1 is a longitudinal section through the improved fountain pen. Fig. 2 is a longitudinal section taken on the line 2—2 in Fig. 1. Figs. 3 and 4 are similar sections of modifications of the means for securing the protecting shell in its outmost position. Fig. 5 is a longitudinal section through a fountain pen with further modifications. Fig. 6 is a longitudinal section taken on the line 6—6 in Fig. 5. Fig. 7 is a longitudinal sectional view showing the pen in the writing position, and Fig. 8 is a detail transverse sectional view on the line 8—8 of Fig. 1 and on a somewhat enlarged scale.

The illustrated fountain pen has an outer tube 2 to which an inner tube 4 is secured which 50 forms or carries the nib holder. Between the tubes 2 and 4 a tubular shell 1 is slidable, which protects the nib and is provided with a lid 5 at its outer end which is opened as soon as the shell 1 is moved outwardly along the member 2.

55 In order to prevent the protecting shell 1 when

in its outmost position from casually moving inwardly and entering the outer tube 2, a longitudinal elastic tongue or spring 24 is secured on the inner wall of the inner tube 4 say by riveting, the free end of such spring extends through 60 a slot in the inner tube and is provided with a rounded projection 25, which extends outwards and snaps over the inner edge 6 or in a rest 7 of the protecting shell 1, when the latter is completely moved outwards, so that said shell is 65 sufficiently held in said position. By a slight pressure the projection 25 or the spring 24 yields, so that the shell 1 may be moved inwards.

Instead of a separated spring or tongue, a 70 tongue 26 (Fig. 5) may be provided, which is formed by cutting the wall of the inner tube 4 (Fig. 2). In both cases the tongue may also be provided with a bent end 27 (Figs. 4, 5), which replaces the aforesaid projection and 75 snaps over the inner edge 6 or in a rest 7 of the shell 1 (Figs. 1, 2).

Moreover a similar separate or cut out longitudinal tongue or spring 28 (Figs. 5, 6) may be provided, the bent portion of which engages a 80 longitudinal groove 29 of the shell 1 and is guided therein, so that the shell 1 is prevented from rotating about the inner tube 4 or in the outer tube 2. For the same purpose a small screw 30 (Fig. 1) may be screwed in the wall of 85 the inner tube 4, which may be provided therewith a reinforcing ring 31 in order to afford the required thread for the screw 30. The head of such screw engages the inner longitudinal groove 90 29 of the shell 1.

What I claim is:

1. A fountain pen comprising an inner shell forming a nib carrier, an outer shell at the outer end of the inner shell and spaced therefrom, said inner shell having a longitudinally arranged stop spring, free to move outwardly at its end nearest the nib, and a protecting shell 95 slidably mounted between the inner and outer shells and having a stop shoulder at its inner end, engageable directly by the free end of the spring tongue to lock said protecting shell when the same is drawn outwardly to enclose and protect the nib.

2. In a fountain pen, a tubular system comprising an outer tube and an inner tube connected thereto and forming the nib carrier, a protecting shell slidably mounted on the inner and in the outer tube, and having a longitudinal groove, said inner tube having a member engag- 105 110

ing said groove and projecting outwardly from the wall of the inner tube.

3. In a fountain pen, a tubular system comprising an outer tube and an inner tube connected thereto and forming the nib carrier, a protecting shell slidably mounted on the inner

and in the outer tube, and having a longitudinal groove, said inner tube having a projecting member engaging said groove, said member passing through the inner tube and screwed into a reinforcing ring in the latter.
